METHOD OF AND APPARATUS FOR ANNEALING GLASSWARE

Walter O. Amsler, Toledo, Ohio, assignor to Hartford-Empire Company, Hartford, Conn., a corporation of Delaware

Application May 18, 1936, Serial No. 80,254

27 Claims.

(Cl. 49—47)

This invention relates to a method of and apparatus for annealing glassware, and more particularly to such a method and apparatus where in the glassware is passed through an annealing lehr of the elongate tunnel-type and heat is transferred longitudinally of the tunnel by mechanical means, such as a mass of high heat capacity, moving longitudinally of and within the tunnel at a speed substantially independent of the speed of movement of the glassware, in order to control the temperature gradient in the tunnel and hence that in the ware passing therethrough.

In the prior art of some time ago, the annealing of glassware was accomplished by passing the ware upon relatively solid and heavy metallic conveyors of high heat mass through annealing tunnels which were of heavy masonry construction. Due to the lack of adequate temperature control and due to the high heat mass of the conveyors, the results were relatively unsatisfactory as compared with most modern lehrs.

One of the difficulties with which such old lehrs had to contend was the effect of the movement of the high heat mass conveyor longitudinally of the tunnel, resulting in the movement of heat along the tunnel at a speed and in such amount that it could not be controlled to produce a desired temperature gradient independently of the speed of movement of the ware, as the movement of heat was accomplished by the same conveyor by which the ware was transported through the tunnel. This was the case whether the return strand of the conveyor was outside or within the tunnel for all or part of its length.

More recently the art has developed along the lines of providing lighter and more flexible annealing apparatus or lehrs, which may be controlled in steps or zones along their lengths to establish substantially a desired temperature gradient. However, in all such modern lehrs there may be sudden, if small, drops in the temperature in the tunnel at the points where the specific temperature control is effected.

It is also known that the desired temperature gradient in glassware passing through a tunnel is smooth and uninterrupted by any abrupt changes in temperature except possibly as hereinafter pointed out. This desired smooth gradient should start adjacent to the entrance end of the lehr at a relatively high point, usually between 1000 and 1100° F. for most types of glassware, and drop at a relatively slow but substantially smooth and continuous rate until the ware reaches its "low annealing point", by which is

meant the temperature below which permanent strains cannot be introduced into the ware. That is, ware below this temperature may be subjected to temporary strains due to temperature differences in different parts of an article which may and sometimes do increase to the point of breaking the ware. However, if ware is properly annealed in bringing its temperature down to and through the "low annealing point", any strains introduced thereafter at lower temperature ranges, if they do not break the ware during the cooling, will disappear when the article is finally cooled, to the end that the article as finally cooled will have the identical strain characteristics of that article when it has been brought down to its low annealing point. It is usual in glass annealing lehrs to increase the rate of cooling subsequent to bringing the ware down to its low annealing point, to the highest rate which can normally be maintained without subjecting the articles being annealed to strains sufficient to rupture them.

Among the objects of my present invention is to provide a method and an apparatus which will enable the maintenance in a lehr of the desired smooth temperature gradient without abrupt changes by the use of one or more moving masses of high heat capacity, in which the movement of these "heat conveyors" as they may be called is not limited by the movement of the ware through the tunnel.

A further object of the present invention is to provide a novel method and apparatus as above set forth by which heat may be drawn forwardly of the lehr, that is, toward the ware-entering end thereof to provide the desired relatively high temperature at this end.

A further object of the present invention is to provide for the use of a heat conveyor, that is, a movable means of high heat capacity in the cooling portion of the tunnel for assisting in the abstracting of heat from the ware in order to accelerate the normal rate of cooling thereof, while at the same time maintaining a desired temperature gradient in the ware passing through this portion of the tunnel.

Further objects and advantages of my present invention will become apparent from the following specification and appended claims when taken in connection with the accompanying drawings, in which:

Figures 1 and 2, when placed end to end, make up a view substantially in vertical longitudinal section of an annealing lehr constructed according to my invention, and for carrying out the

methods thereof, the view being diagrammatic in character;

Fig. 3 is a view substantially in vertical transverse section taken on the line 3—3 of Fig. 1;

5 Fig. 4 is a view substantially in vertical transverse section taken on the line 4—4 of Fig. 2; and

10 Figs. 5 and 6 when placed end to end illustrate a modified form of annealing lehr also embodying my invention, the view being in vertical longitudinal section similar to Figs. 1 and 2.

15 Referring now to Figs. 1 to 4 wherein I have diagrammatically illustrated a lehr embodying my invention, there is shown a tunnel 1, which may be built up in any suitable or desired manner, such as those now well known in the art, and includes insulated top, side and bottom walls 2, the insulation being tapered as illustrated at 3, Fig. 2, and terminating substantially at the point 4 in that figure, so that the remainder of 20 the tunnel indicated at 5 may be uninsulated and of any suitable construction, usually of sheet metal. The tunnel 1 and its insulation are shown as supported conventionally upon a plurality of legs 6, which may rest directly on the floor, as 25 shown, or may be provided with suitable wheels or casters to permit the movement of the lehr as desired. Inasmuch as such wheels or casters are old in the art, it is not thought necessary to illustrate them.

30 The ware may be conveyed through the lehr in any suitable manner, but I have chosen to illustrate diagrammatically by parallel broken lines at 7 an endless conveyor, which is preferably of low heat mass and may, for example, be constructed in the same manner as the endless woven wire conveyors now in common use in many commercial glassware annealing lehrs. As shown, both strands of the conveyor 7 extend through the tunnel in the form of the invention shown in Figs. 1 to 4, the conveyor 7 passing around a suitable 40 roller 8 adjacent to the forward end of the tunnel. Suitable means (not shown) may be provided for moving the conveyor 7 in a manner which is now well known in the art, such means being illustrated for example in the patent to Mulholland 45 No. 1,560,481, granted Nov. 3, 1925. Suitable means may also be employed for supporting the ware bearing and return strands of the conveyor 7, but inasmuch as the supporting means form per se no part of the present invention, they 50 have not been specifically illustrated.

55 Means are provided for supplying heat to the tunnel, preferably from beneath the path of the ware, such means in the present instance comprising a fire box 9 having associated therewith a flue or flues 10 extending longitudinally beneath a portion of the tunnel as shown in Fig. 1. The fire box 9 is provided with means for generating hot products of combustion therein, including a burner diagrammatically shown at 11 through 60 which a fluid fuel, such as gas or oil, may be introduced in any suitable manner. There is also admitted to the firebox 9 air to support combustion and also, if desired, to dilute the products of combustion to substantially the temperature 65 to which it is desired to reduce such products before they are introduced into the flues 10. The passage for gases from the fire box 9 to the flues 10 as defined by baffles 12 and 13, so that the 70 gases must pass in a tortuous path in which combustion is normally completed.

75 Means are provided for exhausting the gases from the flues 10, including saddle pipes 14 (Figs. 1 and 3), which may be controlled by suitable dampers, as indicated diagrammatically at 15,

Fig. 1. These pipes both lead the gases to the interior of a hood 16, from which the gases may pass to a stack or outlet pipe 17 leading to some suitable exhaust point. If desired, a damper 18 may be provided in the stack 17 as shown. 5

It will be noted that the interior of the hood 16 also communicates through an opening 19 with the interior of the tunnel and through this opening some of the tunnel atmosphere may pass by the inductive action of the stack to exhaust with 10 the gases from the flue 10. In practice, this may be employed by a relative adjustment of the dampers 15 and 18 to cause an inflow of atmospheric air at the exit end of the lehr serving by its 15 countercurrent flow through the tunnel to assist in cooling the ware in this portion thereof. Flow through the hotter portion of the tunnel, however, is preferably kept at a minimum by maintaining the front door 20 of the tunnel closed as far as possible while leaving an opening of 20 sufficient size for the introduction of the ware.

Other means, such as one or more curtains, as 25 shown at 21, Fig. 5, may be employed along the hotter portion of the tunnel for minimizing the flow of air into the hotter end thereof and out 30 the exhaust opening 19 to the stack. It will be understood that if desired a suitable fan or other exhaust-impelling means, such as are now common in the commercial art, may be employed in conjunction with the passage or stack 17, but that 35 these means per se form no part of the present invention and hence are not illustrated.

With the structure thus far described, no means have been provided other than the normal rate of 40 dissipation of heat from the ware and from the gases passing through the flue 10 for controlling the temperature gradient in the heated portion of the tunnel, which may for practical purposes be considered as that portion extending from the entrance end thereof to a point under the hood 16 where the heated gases are withdrawn 45 from the flue 10 and conducted away from the lehr. Under these circumstances, the desired gradient probably would not be obtained, except possibly where a particular rate of loading of ware having a particular heat content and temperature was being handled.

50 In order to provide a control of the temperature gradient in the hotter zone of the lehr and at the same time to carry heat forwardly to a material extent, I propose to introduce into the tunnel and preferably between the path of the ware and the flue 10 a heat conveyor, which from a broad point of view comprises a mass of material of high heat capacity movable longitudinally 55 of the lehr. The expression, "a mass of high heat capacity", is intended to exclude all gases, such as air and products of combustion. The expression when used hereinafter in the specification and in the appended claims is to be so interpreted and construed. More specifically, the 60 heat conveyor shown at 22 may comprise a relatively heavy pan-type conveyor, similar in some respects at least to the ware conveyors used in the lehrs of the older prior art, the pans or panels being pivotally connected together, so that the 65 conveyor as a whole is an endless flexible metallic means of high heat capacity, the sole purpose of which in this embodiment of the invention is to convey heat.

70 The conveyor 22 is mounted and moved so that the lower strand 23 thereof travels forwardly of the lehr and is supported by the top of the flue 10 so as to be in good heat transferring relation therewith, both by conduction and radiation. The conveyor 22 passes around rollers or sprocket 75

wheels 24 and 25, the latter of which may be driven in any suitable manner. The upper strand of the heat conveyor 22 may be supported, as best shown in Fig. 3, upon suitable angles 26 5 secured to the sides of the lehr tunnel to move in a path immediately below the return or idle strand of the ware conveyor 7 and support it if desired. The directions of movements of the various strands of the two conveyors 7 and 22 are 10 shown by the arrows in Fig. 1.

For driving the heat conveyor 22, the roller or sprocket wheels 25 is mounted upon a shaft 21, which extends through at least one side wall of the lehr and is provided outside the lehr with a 15 suitable pulley or sprocket wheel indicated at 28, which is driven through a flexible driving means 29 from a drive roller or sprocket wheel 30 of a speed changing device 31, which may be of any suitable commercial type now available 20 for purchase in the open market, such, for example, as the "Reeves Drive". The speed changing device 31 may be driven through an endless flexible driving means 32 from a suitable source of power, such, for example, as an electric motor 33. Thus, if it be assumed that the motor 33 or 25 other driving means employed is operated at a constant speed, the speed of the movement of the heat conveyor 22 may still be varied as desired by the speed changing device 31. Also this speed 30 may be and in practice is controlled independently of the speed of movement of the ware conveyor 7, i. e., equal to or different from the speed of the ware conveyor, in order to attain the desired results from the point of view of the temperature gradient in the lehr. In practice, the speed 35 is selected in accordance with the requirements for heat of the ware in passing through the hotter zone of the lehr.

The lower strand 23 of the heat conveyor in 40 moving over the top of the flue 10 will accumulate heat and move it mechanically toward the forward end of the lehr, this effect in practice being much greater than the opposing effect of the upper strand of the heat conveyor 22 moving 45 toward the rear of the lehr and the two strands having a joint effect of maintaining an uninterrupted smooth temperature gradient throughout the zone in which the heat conveyor 22 is located. At the same time the lower strand 23 of the heat 50 conveyor 22 is accumulating heat, the upper strand of the conveyor 22 is giving off its heat to the ware and to the sides and top of the tunnel, so that elements of the heat conveyor arrive at the roller or sprockets 25 at a temperature lower 55 than their temperature at the roller or sprockets 24, thus controlling by the large mass of high heat capacity moving along the lehr the temperature gradient in the tunnel and in the ware. It will be seen by varying the speed of movement of 60 the heat conveyor, the temperature gradient may be adjusted to the desired point to compensate to a material extent at least for variations in the heat input into the tunnel in the glassware, due principally to variations in the weight of glass 65 being loaded into the lehr and to a relatively lesser extent to variations in the temperature at which the glass is introduced into the lehr.

Associated with the cooling portion of the tunnel, which is shown in Fig. 2 and overlapping to 70 a slight extent the longitudinal extent of the heat conveyor 22 (Fig. 1) is a second heat conveyor 34, this conveyor being disposed above the path of the ware and having its lower strand only within the tunnel, the upper strand returning toward the exit end of the lehr above the tunnel.

The heat conveyor 34 passes around an idle roller or sprocket wheels 35 adjacent to the exit end of the tunnel, as shown in Fig. 2, and around a driving roller or sprocket wheels 36, Fig. 1. The lower strand may be supported as shown upon 5 angles 37 suitably secured to the sides of the lehr and the upper strand on angles 38 secured by suitable brackets shown best in Fig. 4 to the top of the lehr on the outside thereof.

The two strands of the conveyor 34 are adapted 10 to move in the direction of the arrows, Figs. 1 and 2, that is, the lower strand within the tunnel moves in the direction opposite that of the movement of the ware through the tunnel. For driving the heat conveyor 34, the roller or sprockets 15 36 is mounted upon a transverse shaft 39, which carries outside the lehr a sprocket wheel or pulley 40, this wheel or pulley being connected by a suitable endless flexible driving means 41 with the driving roller or sprocket 42 of an adjustable 20 speed-changing device 43, which may be similar to the speed-changing device 31 above referred to. The speed changing device 43 may in turn be driven by a suitable flexible driving means 44 by any suitable source of power, which in the 25 present instance is also illustrated as the motor 33.

The lower strand of the heat conveyor 34, which is in heat transferring relation with the ware passing through the cooling portion of the 30 lehr, will accumulate a material amount of heat from the ware due to its large heat mass and will carry this heat outside the lehr where it may be dissipated from the upper or return strand of the heat conveyor to the surrounding atmosphere. 35 Also, due to the countercurrent movements of the glassware and the lower strand of the heat conveyor, this strand will become gradually heated as it moves toward the entrance end of the tunnel, so that the ware at any given part of the 40 tunnel will not be in heat transferring relation with a portion of the conveyor differing too greatly in temperature from the ware. In this way, I am enabled to augment the rate of abstraction of heat and heat dissipation from the ware 45 through the cooler zone thereof and accelerate the cooling to establish a desired temperature gradient in the ware.

Turning now to the form of the invention shown in Figs. 5 and 6, the same reference characters have been used for corresponding parts, as far as possible, and where the parts have been but slightly changed the same reference characters plus an exponent are used. The tunnel of the lehr may be constructed in substantially 50 the same way as previously described, or in any other suitable or equivalent manner, and may be supported also in the same way as described for the previous form of the invention.

The ware is carried through the tunnel of this 60 form upon a conveyor 1a which may be of the same construction per se as that previously described, the difference here being that in this form of the invention the return strand of the ware conveyor is brought back to the entrance 65 end of the lehr beneath the tunnel and passes through a suitable aperture 45, as shown in Fig. 5, to the roller 8 at the entrance end of the lehr, this return strand being supported and guided by suitable spaced rollers 46, 47 and 48 as shown. 70 It will be understood that the driving means for the ware conveyor 1a of this form of the invention may be the same as or similar to that contemplated for use with the form of the invention previously described.

The heat supplying means shown in Fig. 5 associated with the hotter portion of the lehr tunnel may be substantially the same as those previously described and are referred to by the same reference characters, with the exception that the hood 16a is of slightly different form than the hood 16, due to the fact that the heat conveyors associated with this form of the invention, as hereinafter to be described, do not overlap one another longitudinally of the lehr.

In this case, the heat conveyor 22 is essentially the same as the correspondingly numbered heat conveyor, shown in Fig. 1 and is similarly mounted for movement upon rollers or sprocket wheels 24 and 25, the latter being driven by being mounted upon a shaft 27 to which is secured a driving sprocket or pulley 28 driven by a flexible driving means or belt 29 from the speed changing device 31, and that device similarly receiving its power from a motor 33a. In this case, however, the motor 33a is employed solely for driving the heat conveyor in the hotter end of the lehr and a separate motor hereinafter to be described is employed for driving the other heat conveyor.

25 This modification may be resorted to if desired.

As shown, the motor 33a has connected therewith line wires 49 having a suitable switch conventionally illustrated at 50 interposed therein, so that the motor 33a may be stopped if desired, 30 in order that the heat conveyor 22 be completely stopped while the heat conveyor in the cooler portion of the lehr later to be described may be continued in operation. It is contemplated that this manner of operation may be employed should 35 it be desired.

Intermediate the upper and lower strands of the heat conveyor 22 as shown in Fig. 5, I provide a means for retarding the passage of heat between the strands of the heat conveyor, such means being generally indicated as a wall 51. This wall may also be of varying thickness or of heat transferring ability from end to end thereof, and as shown is relatively thinner toward the hotter end of the lehr and relatively thicker toward the cooler end thereof. In practice, this wall may be made up of a plurality of independently adjustable louvres 52 which, when all are closed, form the wall as shown. Any suitable means may be employed outside the lehr for effecting an adjustment of the individual louvres 52, such for example as hand cranks associated with each of the louvres. Also, if desired, any suitable means such as are known in the art for effecting progressive adjustments in bank of a plurality of the louvres 52 may be employed, but inasmuch as such means per se form no part of the present invention they have not been illustrated. By the provisions shown and hereinbefore described, I am enabled to control with substantial accuracy 50 the temperature gradient in the hotter portion of the lehr, these adjustments including the adjustment of the rate of heat supply to the fire box 9 and the draft therefrom, the adjustment of the speed of movement of the heat conveyor 60 22 and the adjustment of the several louvres.

Also in Fig. 5, in the hotter zone of the lehr, I have illustrated a further modification of the Fig. 1 form of the invention, in which a material portion at least of the ware conveyor 1a 70 is supported directly upon the upper strand of the heat conveyor 22. This arrangement may be resorted to if desired. It will be understood, however, that under these circumstances, the speed of the heat conveyor is only partially independent 75 of the speed of the ware conveyor, as it is in

practice undesirable to operate the heat conveyor faster than the ware conveyor, due to the fact that the ware-bearing strand of the latter is normally under tension, being drawn through the lehr by the driving means associated therewith. If the heat conveyor should move faster than the ware conveyor, it would tend to buckle up portions of the latter and upset the ware thereon. Within those limits, however, the heat conveyor may be moved at any desired speed 10 slower than that of the ware conveyor, or at the same speed. This limitation, however, is not present in the form of the invention shown in Fig. 1, as the adjacent strands of the two conveyors are traveling in opposite directions, as 15 is indicated by the arrows in that figure.

The heat conveyor 34 shown in Figs. 5 and 6 may be constructed, mounted and operated in substantially the same way as the corresponding means previously described, the principal difference being that the driving roller or sprockets 36 are disposed further along the lehr than the correspondingly numbered means of Fig. 1. The drive for the shaft 39 through the flexible driving means 41 and speed changing device 43 is 25 effected by a separate motor 33b, which has its own individual power line supply 49b and switch 50b. In this way the two heat conveyors may be operated not only at independent speeds but either may be stopped entirely without interfering 30 with the operation of the other.

In addition in Fig. 6, I have shown a means for accelerating the cooling or rate of heat dissipation from the upper strand of the heat conveyor 34 above the lehr, such means in the present 35 instance comprising a blower 53 arranged to direct a stream of air through a nozzle 54 onto the upper strand of the heat conveyor 34 and thus accelerate the cooling thereof prior to the entrance of portions of the conveyor into the lehr. 40 The blower 53 may be driven by any suitable source of power, here diagrammatically illustrated as an electric motor 55. It will be understood that any suitable means may be used for accelerating the cooling of the heat conveyor as 45 may be desired in order to meet actual conditions in the use of the device.

By the use of means such for example as those herein disclosed, and by the practice of the method as herein taught, I am enabled to obtain 50 a desired temperature gradient in a lehr and substantially to eliminate any sharp breaks or variations in this gradient, except perhaps at some point adjacent to the boundary between the heated zone of the lehr and the cooling zone 55 thereof, and even here especially by the use of overlapping heat conveyors as shown in Fig. 1, this variation in the rate of cooling or heat dissipation from the ware during its annealing may be made a relatively smooth curve. Also, by the 60 several means hereinabove described, I am enabled to control accurately the temperature gradient in the lehr and to obtain the desired gradient within relatively narrow limits. It will be understood that the temperature gradient will 65 normally be so disposed longitudinally of the lehr in coordination with the speed of movement of the ware that the transition point or zone between the heated portion of the lehr and the cooling portion thereof will be made to approximate 70 the point where the glassware passing therethrough is cooled through its low annealing temperature or point as above defined, so that the rate of cooling of the ware through its annealing range, that is, the range above the low an- 75

nealing temperature or point may be maintained at one value, while the rate of cooling below this point may be maintained at another and different value.

5 It will be understood that while I have illustrated two embodiments of my invention, various changes may be made therein and certain of the independent features may be used without others; for example, but one heat conveyor may be employed in a portion of a lehr with advantage over certain prior art methods or types of construction. I do not wish to be limited, therefore, except by the scope of the appended claims, which are to be construed as broadly as the state of the 10 prior art permits.

I claim:

1. The method of annealing glassware, which comprises establishing and maintaining in an insulated tunnel a selected temperature gradient, 20 by moving a mass of high heat capacity within and longitudinally of said tunnel at a rate selected in accordance with the heat characteristics of the tunnel and of the ware to be annealed, and passing the ware through the tunnel to effect its annealing.

2. The method of annealing glassware, which comprises conveying glassware through an elongate tunnel, applying heat to the tunnel beneath the ware, and regulating the temperature gradient through a portion of the tunnel to effect a given stage of annealing by moving a body of high heat capacity longitudinally of the tunnel beneath the ware at a rate selected so as to establish a desired temperature gradient in the ware.

3. The method of annealing glassware, which comprises passing the ware through an elongate tunnel, establishing and maintaining in the tunnel a selected temperature gradient, and regulating the temperature gradient longitudinally of the tunnel by moving therethrough a mass of high heat capacity at a rate selected in accordance with the heat characteristics of the tunnel and of the ware to be annealed and independent of the rate of movement of the ware therethrough.

4. The method of annealing glassware, which comprises passing the ware through an elongate tunnel, supplying heat to the tunnel beneath the path of the ware therethrough, moving a mass of high heat capacity longitudinally of the tunnel 50 in a path intermediate the source of heat supply thereto and the path of the ware to establish and maintain a smooth temperature gradient in the portion of the tunnel through which the high heat capacity mass travels, and selectively controlling the rate of movement of the high heat capacity mass in accordance with the temperatures in the portion of the tunnel through which it is moved.

5. The method of annealing glassware, comprising passing the ware through an elongate tunnel, and regulating the temperature gradient in a portion at least of said tunnel by moving a mass of high heat capacity in said tunnel in an orbital path having its principal dimension longitudinally of said tunnel.

6. The method of annealing glassware, which comprises passing the ware through an elongate tunnel, passing heated gases in a path longitudinally of said tunnel and in heat transferring relation therewith but out of contact with the glassware along a portion of said tunnel, moving a mass of high heat capacity longitudinally of said tunnel and wholly within said portion thereof, and controlling the temperature gradient in 70 said tunnel by controlling the amount of heat

supplied thereto and the rate of movement of said mass in coordination with the amount of glassware passing therethrough and the rate of its movement to establish a desired temperature gradient in said portion of the tunnel.

7. The method of annealing glassware, which comprises passing the ware through an elongate tunnel, and causing a flow of heat longitudinally of the tunnel by moving therewith a mass of high heat capacity at a speed independent of the speed of movement of the ware therethrough.

8. The method of annealing glassware, comprising passing the ware through an elongate tunnel, causing a flow of heat longitudinally of the tunnel in a hotter zone thereof by moving 15 therewith a mass of high heat capacity at a speed independent of the speed of movement of the ware therethrough, and causing a flow of heat longitudinally of the tunnel in a cooler zone thereof by moving along said cooler zone and 20 within the tunnel another mass of high heat capacity at a speed independent of the speed of movement of the ware therethrough.

9. The method of annealing glassware, which comprises passing the glassware through an elongate tunnel, and causing a flow of heat longitudinally of a cooling portion in said tunnel by moving therewith in such portion a mass of high heat capacity at a speed independent of the speed 25 of movement of the ware therethrough.

10. The method of annealing glassware, which comprises passing the ware through an elongate tunnel, causing a flow of heat longitudinally of the hotter portion of said tunnel by moving therewith in such portion a mass of high heat capacity, causing a flow of heat longitudinally of the tunnel in a cooler portion thereof by moving therewith in such cooler portion a mass of high heat capacity, and controlling the temperature 35 gradient longitudinally of said tunnel by independently regulating the speeds of movement of the masses of high heat capacity moving in the hotter and cooler portions of the tunnel respectively in such manner that both masses will be moved at speeds independent of each other and 40 of the speed of movement of the ware through the tunnel.

11. Apparatus for annealing glassware, comprising an elongate tunnel, means for conveying glassware therethrough, a mass of high heat 50 capacity separate and distinct from said conveying means, and means for moving said mass in and longitudinally of said tunnel to convey heat longitudinally thereof.

12. Apparatus for annealing glassware, comprising an elongate tunnel, means for conveying glassware therethrough, a mass of high heat capacity separate and distinct from said conveying means, means mounting said mass for movement in an orbital path at least a part of which 60 lies in and longitudinally of said tunnel, and means for moving said mass along said path.

13. Apparatus for annealing glassware, comprising an elongate tunnel, means for conveying glassware therethrough, an endless flexible heat 65 conveying means separate and distinct from said glassware conveying means, means mounting said heat conveying means for movement in respect to said tunnel and with at least one strand thereof movable in and longitudinally of said tunnel, and means for moving said heat conveying means.

14. Apparatus for annealing glassware, comprising an elongate tunnel, means for conveying glassware therethrough, a mass of high heat 70 capacity separate and distinct from said conveying

ing means, means for moving said mass in and longitudinally of said tunnel to convey heat longitudinally thereof, and means for adjustably varying the speed of movement of said mass for 5 controlling the temperature gradient in said tunnel.

15. Apparatus for annealing glassware, comprising an elongate tunnel, means for conveying glassware therethrough, means for supplying heat to a portion of said tunnel, a mass of high heat capacity separate and distinct from said conveying means, and means for moving said mass in and longitudinally of said portion of said tunnel to convey heat longitudinally thereof. 10

15. 16. Apparatus for annealing glassware, comprising an elongate tunnel, means for conveying glassware therethrough, means for supplying heat to a portion of said tunnel from beneath the path of the ware therethrough, a mass of high heat capacity separate and distinct from said conveying means, and means for moving said mass in a path intermediate said heat supplying means and the path of the ware for distributing the heat supplied to said tunnel and establishing a 20 desired temperature gradient in the portion of 25 the tunnel to which the heat is supplied as aforesaid.

17. Apparatus for annealing glassware, comprising an elongate tunnel, means for conveying glassware therethrough, means for supplying heat to a portion of said tunnel from beneath the path of the ware therethrough, an endless flexible heat conveying means separate and distinct from said conveying means, means mounting said 30 heat conveying means for movement in an orbital path in and longitudinally of said tunnel and intermediate the portion to which heat is directly supplied and the path of the ware, means for moving said heat conveying means along its path, 35 and means for adjustably varying the speed of movement of said heat conveying means for controlling the temperature gradient in the heated portion of said tunnel.

18. Apparatus for annealing glassware, comprising an elongate tunnel, means for conveying glassware therethrough, a mass of high heat capacity separate and distinct from said conveying means, means for moving said mass in heat transferring relation with the ware during its 45 passage through a cooling portion of said tunnel to absorb heat from the ware and thence for moving said mass to a place where heat absorbed thereby from the ware may be dissipated therefrom. 50

55. 19. Apparatus for annealing glassware, comprising an elongate tunnel, means for conveying glassware therethrough, an endless flexible heat conveying means having one strand disposed within said tunnel in heat transferring relation 60 with the glassware passing through the cooling portion thereof and the other strand outside said tunnel, and means for mounting and moving said heat conveying means in such manner that the strand thereof within said tunnel is moved there- 65 along in the direction opposite that of the movement of the ware therethrough.

70. 20. Apparatus for annealing glassware, comprising an elongate tunnel, means for conveying glassware therethrough, an endless flexible heat conveying means associated with the cooling portion of said tunnel and having its lower strand movably mounted in said tunnel above the path of the movement of the ware therethrough and its upper strand disposed above the 75 tunnel, means mounting said heat conveying

means for movement as aforesaid, means for moving said heat conveying means in such manner that the lower strand thereof moves toward the hotter end of said tunnel, and means for adjustably controlling the speed of movement of 5 said heat conveying means to control the rate of abstraction of heat from the ware thereby and thus to control the temperature gradient in the ware in passing through the cooling portion of the tunnel. 10

21. Apparatus for annealing glassware, comprising an elongate tunnel, means for conveying glassware therethrough, a mass of high heat capacity and separate and distinct from said glassware conveying means disposed for movement in 15 the hotter portion of said tunnel, means for moving said mass in and longitudinally of the hotter portion of said tunnel to convey heat longitudinally thereof, a second mass of high heat capacity and separate and distinct from said 20 glassware conveying means disposed in the cooler portion of said tunnel, and means for moving said second mass at least partly within and longitudinally of the cooler portion of said tunnel for conveying heat longitudinally of such portion. 25

22. Apparatus for annealing glassware, comprising an elongate tunnel, means for conveying glassware therethrough, means for supplying heat to a portion of said tunnel from beneath the path of the ware therethrough, an endless flexible 30 heat conveying means having both strands thereof disposed in said portion of the tunnel intermediate the heat supplying means and the path of the ware therethrough, means for moving said heat conveying means in its path for controlling 35 the transmission of heat from the heat supplying means to the ware and the distribution of heat longitudinally of said tunnel portion, and means intermediate the upper and lower strands of said heat conveying means for controlling the 40 transmission of heat between said strands.

23. Apparatus for annealing glassware, comprising an elongate tunnel, means for conveying glassware therethrough, means for supplying heat to a portion of said tunnel from beneath the path 45 of the ware therethrough, an endless flexible heat conveying means having both strands thereof disposed in said portion of the tunnel intermediate the heat supplying means and the path of the ware therethrough, means for moving said heat conveying 50 means in its path for controlling the transmission of heat from the heat supplying means to the ware and the distribution of heat longitudinally of said tunnel portion, and a wall of varying thickness longitudinally of the tunnel intermediate the upper and lower strand of said heat conveying means for controlling the transmission 55 of heat between said strands.

24. Apparatus for annealing glassware, comprising an elongate tunnel, means for conveying 60 glassware therethrough, means for supplying heat to a portion of said tunnel from beneath the path of the ware therethrough, an endless flexible heat conveying means having both strands thereof disposed in said portion of the tunnel intermediate the heat supplying means and the path 65 of the ware therethrough, means for moving said heat conveying means in its path for controlling the transmission of heat from the heat supplying means to the ware and the distribution 70 of heat longitudinally of said tunnel portion, and a plurality of louvres disposed between the upper and lower strands of said heat conveying means for controlling the transmission of heat therebetween and thereby for controlling the 75

temperature gradient in said portion of the tunnel.

25. Apparatus for annealing glassware, comprising an elongate tunnel, means for conveying glassware therethrough, means for supplying heat to a portion of said tunnel from beneath the path of the ware therethrough, an endless flexible heat conveying means having both strands thereof disposed in said portion of the tunnel intermediate the heat supplying means and the path of the ware therethrough, means for moving said heat conveying means in its path for controlling the transmission of heat from the heat supplying means to the ware and the distribution of heat longitudinally of said tunnel portion, means for adjustably varying the speed of movement of said heat conveying means, and a plurality of independently adjustable louvres so constructed and arranged that when all are closed they form a wall intermediate the upper and lower strands of said heat conveying means, the adjustment of said louvres operating in conjunction with the adjusted speed of movement of said heat conveying means to control the temperature gradient in said portion of the tunnel.

26. Apparatus for annealing glassware, comprising an elongate tunnel, means for conveying glassware therethrough, an endless flexible heat conveying means having one strand disposed within said tunnel in heat transferring relation with the glassware passing through the cooling

portion thereof and the other strand outside said tunnel, means for moving said heat conveying means in such manner and direction that the strand thereof within said tunnel is moved in the direction opposite that of the movement of the ware therethrough, and means cooperating with the strand of said heat conveying means outside said tunnel for increasing the rate of cooling thereof over that rate which would normally take place due to heat dissipation at the place where the annealing apparatus is located.

27. Apparatus for annealing glassware, comprising an elongate tunnel, means for conveying glassware therethrough, an endless flexible heat conveying means having one strand disposed within said tunnel in heat transferring relation with the glassware passing through the cooling portion thereof and the other strand outside said tunnel, an aperture in the wall of said tunnel through which said heat conveying means passes in moving from its course within the tunnel to its course outside the tunnel, means for mounting and moving said heat conveying means in its path to control the temperature gradient in the cooling portion of said tunnel, and means for withdrawing from said tunnel through said opening some of the tunnel atmosphere to prevent inflow of atmospheric air into the tunnel through said opening and to cause a flow of air into at least one end of said tunnel and longitudinally thereof to said opening.

WALTER O. AMSLER.
